UNITED STATES PATENT OFFICE.

MARGARET GLOSSOP, OF SEATTLE, WASHINGTON.

DESIGN FOR A COMBINATION TOOL.

60,135.

Specification for Design.

Patented Jan. 3, 1922.

Application filed July 13, 1921. Serial No. 484,500. Term of patent 14 years.

To all whom it may concern:

Be it known that I, MARGARET GLOSSOP, a citizen of the United States, residing in the city of Seattle, in the county of King and State of Washington, have invented a new, original, and ornamental Design for a Combination Tool, of which the following is a specification, reference being had to the accompanying drawings, forming a part thereof.

In the drawings, Figure 1 is a top plan view of my combination tool.

Fig. 2 is a view in side elevation of the same.

Fig. 3 is an inverted top plan view of my combination tool, and

Fig. 4 is a view in side elevation of my tool in an inverted position.

What I claim is:

The ornamental design for a combination tool as shown.

MARGARET GLOSSOP.
